WINDOW PLANTER

Richard E. Penniman, Narberth, Pa., assignor to Safeguard Products Corporation, North Wales, Pa., a corporation of Pennsylvania

Filed Dec. 13, 1967, Ser. No. 9,753

Term of patent 7 years

(Cl. D35—3)

FIG. 1 is a plan view of a window planter made in accordance with this invention;

FIG. 2 is a front elevational view of the planter of FIG. 1;

FIG. 3 is a rear elevational view of the planter of FIG. 1;

FIG. 4 is a bottom view of the planter of FIG. 1;

FIG. 5 is an end elevational view of the planter of FIG. 1;

FIG. 6 is an enlarged view of the area indicated in FIG. 1 showing the configuration of the expanded metal bottom of the planter;

FIG. 7 is a sectional view of the planter taken along line 7-7 of FIG. 1; and

FIG. 8 is a sectional view of the planter taken along line 8-8 of FIG. 1.

I claim:

The ornamental design for a window planter, substantially as shown.
